UNITED STATES PATENT OFFICE

2,301,323

ATOMIZER

Howard F. Reichenbach, Waterbury, Conn., assignor to Chase Brass & Copper Co. Incorporated, Waterbury, Conn., a corporation

Application February 28, 1941, Serial No. 381,036

5 Claims. (Cl. 299—88)

The present invention relates to improvements in atomizers, that is to say, devices by means of which perfume and other liquids may be converted into and projected as a fine spray.

One of the objects of the present invention is to provide a superior atomizer which is reliable and effective in use and which may be produced at a low cost for manufacture.

Another object of the present invention is to provide a superior atomizer having a novel construction and arrangement of parts, whereby a flexible air-pressure bulb may be conveniently organized with a supporting-member in a leak-proof manner.

A further object of the present invention is to provide a superior atomizer wherein a flexible air-pressure bulb may be freely compressed or flexed to a maximum degree for a given size of such bulb, to thereby expel a maximum amount of air and hence a maximum amount of the liquid being sprayed.

With the above and other objects in view, as will appear to those skilled in the art from the present disclosure, this invention includes all features in the said disclosure which are novel over the prior art.

In the accompanying drawing, in which certain modes of carrying out the present invention are shown for illustrative purposes:

Fig. 1 is a view in side elevation of an atomizer constructed in accordance with the present invention;

Fig. 2 is a top or plan view thereof with the bulb removed;

Fig. 3 is an underside view of the bulb, detached;

Fig. 4 is a broken view in vertical central-longitudinal section, taken on the line 4—4 of Fig. 1 but on a larger scale;

Fig. 5 is a transverse sectional view taken on the line 5—5 of Fig. 4;

Fig. 6 is a broken perspective view in central-longitudinal section of the atomizing-head; and

Fig. 7 is a similar view of the air-pressure bulb, detached.

The atomizer herein chosen for purposes of illustrating the present invention, presents the exterior appearance of comprising three main elements, namely, a container 10, a head-shell 11 and a flexible air-pressure bulb 12. The said head-shell 11 and the container 10 are normally organized together to constitute a "container-unit" to the upper portion of which the said bulb 12 may be attached. The container 10 may be formed of any suitable material such, for in-

stance, as glass, synthetic resins, etc., and as is shown particularly well in Fig. 4, the said container is contracted at its upper end to provide an externally-threaded tubular neck 13 communicating with the hollow interior of the container 10 proper.

The air-pressure bulb 12 is formed of any suitable flexible material such, for instance, as rubber, rubber compounds, and the like, and in the 10 instance shown, is provided in the center of its top with an air-inlet port 14. Generally speaking, the bulb 12 may be said to be of inverted cup-shaped form and is provided adjacent its lower end with an inwardly-projecting annular 15 coupling-bead 15 snugly fitting into an outwardly-opening annular coupling-groove 16 formed in the outer face of the upper portion of the head-shell 11 before referred to. Located above the coupling-bead 15, the bulb 12 is formed with an 20 inwardly-projecting flexible annular sealing-lip 17 having a flat under face or otherwise conforming to the upper surface of an annular sealing-seat 18.

The sealing-seat 18 above referred to constitutes the outer portion of an otherwise concave top-wall 19 forming an integral part of the head-shell 11, which latter is of substantially inverted cup-shaped form.

The bulb 12, in addition to being flexible, is also 30 preferably elastic, and may be formed by molding or any other suitable process so that initially the internal diameter of its annular coupling-bead 15 is materially less than the diameter of the coupling-groove 16 in the outer periphery 35 of the head-shell 11. Under these conditions, the lower portion of the bulb 12 requires stretching in order to enter its coupling-bead 15 into the coupling-groove 16, whereby tight engagement between the said elements is assured.

The head-shell 11 may be conveniently formed 40 from sheet brass and the concave top-wall 19 thereof is centrally perforated to receive a burred-over tubular neck 20 upstanding from a nozzle-head 21 located mainly below the said top-wall and within the confines of the lateral bounds of the skirt-portion of the head-shell 11, as is clearly shown in Fig. 4. Clamped between the upper face of the nozzle-head 21 and the under face of the top-wall 19 of the head-shell 45 11, is the inturned flange of the contracted upper portion 22 of an attaching-shell 23 which also includes a relatively-large-diameter depending threaded skirt-portion 24. The said skirt-portion is internally dimensioned to be threadedly mounted upon the externally-threaded neck 13

50 55

of the container 10, before referred to. Preferably, a resilient washer 25 is installed in the upper portion of the skirt-portion 24 in position to be pressed against the upper edge of the neck 13 of the container 10.

Communicating with the space jointly enclosed by the top-wall 19 of the head-shell 11 and the bulb 12 is a vertical air-passage 26 formed in the nozzle-head 21 and extending part way down from the upper surface thereof. Rigidly installed in the said nozzle-head with its inner end in communication with the air-passage 26 just referred to, is a relatively-small-dia-metered horizontal air-tube 27 which extends radially outwardly concentrically through a horizontally-extending liquid-chamber 28 also formed in the nozzle-head 21.

Surrounding the major portion of the air-tube 27 is a relatively-large-dia-metered nozzle-tube 29 of sufficient internal diameter to accommodate the air-tube 27 with such freedom as to provide a passage of ring-like form in cross section for the purpose as will hereinafter appear. The inner portion of the nozzle-tube 29 terminates short of the vertical central-longitudinal axis of the nozzle-head 21 and is rigidly secured in the outer portion of the liquid-chamber 28 in the said nozzle-head by means of solder, or in any other suitable manner. The outer end of the nozzle-tube 29 extends through an aligned perforation in the side wall of the head-shell 11 and is preferably sealed in said perforation by means of solder or the like. The extreme outer end of the said nozzle-tube 29 is located a short distance beyond the adjacent periphery of the head-shell 11 and is provided with an inturned annular flange 30 defining a central spray-opening 31 spaced outwardly from but in axial alignment with the outer end of the air-tube 27 before referred to.

Rigidly mounted in the nozzle-head 21, in communication with the inner end of the fluid-chamber 28 therein, is a downwardly-extending relatively-rigid liquid-tube 32 located centrally of and extending downwardly through the neck 13 of the container 10. In the particular structure shown, the relatively-rigid liquid-tube 32 has attached to its lower end a flexible liquid-tube 33 which is preferably of sufficient length to have its lower end rest upon the bottom of the container 10, as is shown in Fig. 4. The said flexible liquid-tube may be conveniently formed of braided textile material such as cotton, rayon, or the like.

When the parts are all assembled as shown in the drawing and when the container 10 is provided with a body of liquid 34, the user may grasp the entire device in one hand and by placing a finger over the air-inlet port 14 in the air-pressure bulb 12, the air-space within the said bulb may be sealed. If now the user presses downwardly upon the upper surface of the bulb 12, the entrapped air will be forced through the vertical air-passage 26 in the nozzle-head 21 and will travel thence horizontally outwardly through the horizontal air-tube 27 and ultimately outwardly through the spray-opening 31 in the nozzle-tube 29. The movement of air as just described will cause a suction to be created in the horizontal liquid-chamber 28 of the nozzle-head 21 and also in the parts connected thereto, with the result that the liquid 34 will be drawn upwardly through the flexible liquid-tube 33. The liquid as thus drawn upwardly through the flexible liquid-tube 33 will also pass upwardly through the relatively-rigid liquid-tube 32 into the liquid-chamber 28

of the nozzle-head 21 and thence radially outwardly through the space between the interior of the nozzle-tube 29 and the exterior of the air-tube 27. When the liquid passing through the nozzle-tube 29 reaches a point forwardly of the end of the concentric air-tube 27, the said liquid will be broken up into fine particles and will emerge through the spray-opening 31 in a fine mist intermingled with the emerging air.

Due to the construction and arrangement of parts, the upper portion of the bulb 12 may be depressed downwardly below the annular sealing-seat 18 of the head-shell 11 into substantially the position represented by the dotted lines 35 in Fig. 4. This construction and arrangement of parts enables the maximum amount of air to be forced outwardly through the air-tube 27 without requiring that the bulb 12 or its equivalent be of excessive size.

Furthermore, when the air-inlet port 14 of the bulb 12 is sealed by the finger of the user and the upper portion of the said bulb is pressed downwardly, the annular sealing-lip 17 of the said bulb will by either or both the air pressure and flexing of the said bulb, be forced into sealing engagement with the annular sealing-seat 18 of the head-shell 11. In this manner, the tendency of the compressed air to stretch the coupling-bead 15 of the bulb 12, and thus effecting its escape therearound, is effectively minimized or prevented by the automatic action of the sealing-lip 17. While it is preferred to organize the structure so that the escape of air from within the bulb 12 is prevented by the finger of the user, nevertheless, should it be desired, the said bulb 12 may be equipped in a manner well known in the art with a suitable check-valve.

By providing the head-shell 11 or its equivalent with the attaching-shell 23 or its equivalent, the threaded or similar connection between the container and the said head-shell may be concealed to thus not require the marring of the otherwise symmetrical appearance of the assembly.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An atomizer including in combination: a container-unit having an outwardly-opening annular coupling-groove adjacent its upper end and also having an upwardly-facing annular sealing-seat located in a plane above the said coupling-groove; a flexible air-pressure bulb of substantially inverted cup-shaped form and having an inwardly-projecting annular coupling-bead seated in the coupling-groove of the said container-unit; and a flexible inwardly-projecting annular sealing-lip carried by the said bulb interiorly of itself and at a point above the said coupling-bead thereof and in position to flex downwardly against the upwardly-facing annular sealing-seat of the said container-unit; said air-pressure bulb being constructed and arranged to be flexed inwardly in the direction of the axis of, and transverse to, said annular sealing-seat, whereby the entire annular extent of said sealing-lip is pressed more tightly against said annular sealing-seat.
2. An atomizer including in combination: a

container having a contracted threaded neck at its upper end; a head-shell of substantially inverted cup-shaped form and including an annular skirt-portion and a top-wall; an attaching-shell secured to and projecting downwardly from the top-wall of the said head-shell and threaded-ly engaged with the contracted neck of the said container and housed within the space within the annular skirt of the said head-shell; and a flexible air-pressure bulb of substantially inverted cup-shaped form secured to the upper portion of the said head-shell and extending thereabove.

3. An atomizer including in combination: a container having a contracted threaded neck at its upper end; a head-shell of substantially inverted cup-shaped form and including an annular skirt-portion and a top-wall; an attaching-shell secured to and projecting downwardly from the top-wall of the said head-shell and threaded-ly engaged with the contracted neck of the said container and housed within the space within the annular skirt of the said head-shell; a flexible air-pressure bulb secured to the upper portion of the said head-shell and extending thereabove; and a nozzle-head carried by the top-wall of the said head-shell at a point above the contracted neck of the said container.

4. An atomizer including in combination: a container having a contracted threaded neck at its upper end; a head-shell of substantially inverted cup-shaped form and including an annular depending skirt-portion and a top-wall, the said head-shell being provided adjacent its upper end with an outwardly-opening annular coupling-groove and also having an upwardly-facing annular sealing-seat located in a plane above the said coupling-groove; an attaching-shell secured to and projecting downwardly from

the top-wall of the said head-shell and threaded-ly engaged with the contracted neck of the said container; a flexible air-pressure bulb of substantially inverted cup-shaped form and having an inwardly-projecting coupling-bead adjacent its lower end and seated in the coupling-groove of the said head-shell; and a flexible sealing-lip formed in the interior of the said bulb at a point above the said coupling-bead thereof and in position to flex downwardly against the annular sealing-seat of the said head-shell.

5. An atomizer including in combination: a container; a head-shell of substantially inverted cup-shaped form mounted upon the upper portion of the said container and including an annular skirt-portion and a top-wall, the said head-shell being formed adjacent its upper end with an outwardly-opening annular coupling-groove and also having a portion of its said top-wall shaped to provide an annular sealing-seat located in a plane above the said coupling-groove; a flexible air-pressure bulb of substantially inverted cup-shaped form and having an inwardly-projecting annular coupling-bead seated in the coupling-groove of said head-shell; and a flexible inwardly-projecting annular sealing-lip formed in the interior of the said bulb at a point above the said coupling-bead thereof and positioned to flex against the sealing-seat portion of the top-wall of the said head-shell; said air-pressure bulb being constructed and arranged to be flexed inwardly in the direction of the axis of, and transverse to, said annular sealing-seat, whereby the entire annular extent of said sealing-lip is pressed more tightly against said annular sealing-seat.

HOWARD F. REICHENBACH.
